(57) **CLAIM**

The ornamental design for a handset for furniture, as shown and described.

DESCRIPTION

FIG. 1 is a first top perspective view of a first embodiment of a handset for furniture according to my design;

FIG. 2 is a second top perspective view thereof,

FIG. 3 is a bottom perspective view thereof,

FIG. 4 is an elevational left side view thereof, the right side view being a mirror image,

FIG. 5 is a top plan view thereof,

FIG. 6 is a bottom plan view thereof,

FIG. 7 is an elevational rear end view thereof,

FIG. 8 is an elevational front end view thereof,

FIG. 9 is a first top perspective view of a second embodiment of a handset for furniture according to my design,

FIG. 10 is a second top perspective view thereof,

FIG. 11 is a bottom perspective view thereof,

FIG. 12 is an elevational left side view thereof, the right side view being a mirror image,

FIG. 13 is a top plan view thereof,

FIG. 14 is a bottom plan view thereof,

FIG. 15 is an elevational rear end view thereof,

FIG. 16 is an elevational front end view thereof,

FIG. 17 is a first perspective top view of a third embodiment of a handset for furniture according to my design,

FIG. 18 is a second top perspective view thereof,

FIG. 19 is a bottom perspective view thereof,

FIG. 20 is an elevational left side view thereof, the right side view being a mirror image,

FIG. 21 is a top plan view thereof,

FIG. 22 is a bottom plan view thereof,

FIG. 23 is an elevational rear end view thereof; and,

FIG. 24 is an elevational front end view thereof.
